PAUL H. LANGE, OF BRIDGEPORT, CONNECTICUT, ASSIGNOR TO THE MAX AMS MACHINE COMPANY, OF BRIDGEPORT, CONNECTICUT, A CORPORATION OF NEW YORK.

SYSTEM OF HANDLING CAN BODIES.

Application filed January 17, 1925. Serial No. 2,989.

The present invention relates generally to systems of handling the bodies of tin cans or the like. Machines for making the bodies can run very much faster than machines for heading, i. e. applying covers to bodies, and, as a result of this, it is theoretically economical to couple a plurality of heading machines to the outfeeding means from the body former. It has been found, however, that a stoppage, due to defective feeding of the bodies or interruption in the operation of a heading machine, will clog the whole system; and, since such stoppages may be frequent owing, say, to the absence of a cover at the proper time, the loss in production is relatively large and renders the coupling up of several heading machines to a body former of doubtful value.

It is the object of the present invention to overcome these difficulties and the main, although not the exclusive, feature of the invention is so to group and arrange the devices that stoppage of one machine will not interfere with the operation of the system as a whole.

In the accompanying drawings the invention is disclosed in a concrete and preferred form in which:

Figs. 1^A and 1^B together constitute a dia-
30 grammatic plan view of a system embodying
one form of the invention.

Fig. 2 is an enlarged front elevation of one form of up-ending device.

Fig. 3 is a top plan view of one form of
35 a distributor by means of which the bodies
are taken from the main conveyor and fed
to separate conveyors leading to different
heading machines.

Fig. 4 is a longitudinal vertical sectional
40 view on the plane of irregular line 4—4 of
Fig. 3.

Fig. 5 is a transverse vertical sectional
view on the plane of line 5—5 of Fig. 3.

Fig. 6 is a transverse vertical sectional
45 view on the plane of line 6—6 of Fig. 3.

1 indicates a main central feeding device
or conveyor of conventional type which may
be the out-feed conveyor, or a continuation
thereof, of a body forming machine. Said
50 conveyor is adapted to feed bodies 2 in a con-
stant procession, the bodies being here in re-
cumbent position. The bodies come against
stop or gage 3 and rest upon table 4, the con-
veyor having a downward dip as at 5 (Fig.
55 4) so as to move beneath the body. 6 is a

distributing device that reciprocates trans-
versely over table 4 and moves alternate
bodies in opposite directions to separate aux-
iliary feeding devices or conveyors 7 and 8
that are arranged in parallel, so to speak, or
60 that constitute multiple branches of the main
conveyor. 9 and 10 indicate two heading
machines of a well-known construction, said
machines having rotatable turrets and an au-
tomatic cover feed mechanism, the latter in-
65 dicated at 11. In case it is desired to apply
covers to both ends of the body, as in fric-
tion top cans, there may be other heading
machines, such as 12 and 13 in series, so to
speak, with machines 9 and 10, and the ma-
chines are then arranged in two independent
70 groups with the machines of each group in
series, there being body-feeding devices 14
and 15 between machines of the same group.

In the present instance the distributing de-
vice is constructed as follows: (Figs. 3, 4, 5
and 6) distributing member 6 is mounted on
a slide 17 adapted to reciprocate on trans-
versely extending rail 18. 19 is a support
having side beams 20 carrying the slide rail
and also supporting cross beam 21. Carried
by the cross beam is an adjustable friction
plate 22 between which and table 4 the can
body slides. 23 are spring friction plates,
also carried by the cross beam, beneath
which the bodies slide as they pass from
the main conveyor to auxiliary conveyors.
Any suitable actuating means may be pro-
vided for effecting reciprocation of slide 17
but in the present instance these means take
the following form: motion is imparted to
crank disc 24 by means of bevel gears 25
and 26. Disc 24 and gear 26 are mounted on
a stub shaft 27. 28 is a rockshaft mounted
in the framework and provided with a con-
nection 29 attached to the slide by means of
link 30. Rockshaft 28 also carries a slotted
guide 31. 32 is another rockshaft also
mounted in the framework and having an
arm 33 pivotally connected to links 34 and
35, the former of which is connected to
crank pin 36 of disc 24 and the latter of
which carries a square block 37 sliding in
slotted guide 31. It will now be understood
that rotation of the crank disc causes oscil-
lation of links 34 and 35 thereby causing
block 37 to slide in guide 31 and thereby
also causing rockshaft 28 to oscillate which,
in turn, imparts motion to arm 29 and link
30 thereby causing reciprocation of slide 17.

It will be understood that the parts are so timed that member 16 is at one side of a body arriving against stop 3 and that its transverse travel will move said body, say, 5 to conveyor 7 and that on its return movement it will move the next body to conveyor 8. Should there be a stoppage of conveyor 8 so that a body is not removed by said conveyors, then the next body arriving will 10 crowd the first body out of the machine as shown in Fig. 5, there being a by-pass at that point. If desired a gate 38 hinged at the top on bracket 39 carried by the side beam may be provided at each side of the 15 machine and this gate will act as a guide or stop, its weight being sufficient to accomplish this purpose but not sufficient to prevent a body, under the influence of member 6, from being pushed out of the machine. 20 It will now be understood that should a stoppage occur in conveyor 8, the bodies will be thrown out of the machine through the by-pass and the action of conveyor 7 will not be affected and vice versa. At the 25 termination of conveyor 7 is an up-ending device 40 consisting here of a star wheel that has a progressive intermittent motion, the body coming to rest in a recumbent position on one of the arms of said device (Fig. 2). 30 A quarter turn of 40 brings the body into an upright position and a pusher 41 actuated by a suitable cam moves the body in upright position into the turret of a heading machine. The details of this feature of the 35 machine are disclosed in application Ser. No. 602,505 filed November 22, 1922. There is a by-pass also at this point in the system, and it will be understood that should pusher 41 for some reason fail to operate, the next 40 quarter turn of up-ending device 40 will throw the body out of the machine. Preferably the action of the pusher is governed by a detector 42 that permits action of the pusher so long as a cover 43, from the cover 45 stack or feeding device 11, passes a given point at a given time but, should there be no cover, the pusher will not operate and the body will be ejected. It will be understood that there is a similar arrangement at 50 the infeeding point of each heading machine.

At the exit end of machine 9, the body, with cover attached, slides over table 44 in an upright position and said table is cut 55 away so that at the proper moment the body becomes overbalanced and falls in a recumbent position on conveyor 14 that leads to the next machine in series with the first. Should conveyor 14 fail to take away the 60 body, it will be ejected through the by-pass located at the outfeed point of machine 9 by the next succeeding body. Conveyor 14 feeds the recumbent body to an up-ending device 40^a and a pusher 41^a located adjacent 65 the in-feed point of machine 12, the con-

struction here being the same as that previously described in connection with machine 9. The body is, however, here up-ended reversely from its position in machine 9 so that a cover may be attached to its other end. Should now machine 12 or conveyor 14 fail to operate not only will machines 10 and 13 continue in operation but machine 9 will likewise act uninterruptedly. Simular by-passes and up-ending devices are 75 associated with machines 10 and 13 and conveyors 8 and 15 and a repetition of the description of the action is not necessary.

I claim:

1. A system of handling bodies including: two heading machines, a main body-feeding device to advance a procession of bodies, two auxiliary body-feeding devices arranged in parallel and each including one of the heading machines, a distributing device to separate the procession of bodies and to feed them to the auxiliary body-feeding devices, and a by-pass associated with each auxiliary body-feeding device through which excess bodies will be discharged by the distributing 90 device in case of interruption in the normal operation of an auxiliary feeding device.

2. A system of handling bodies including: two heading machines, separate body-feeding devices for each machine, a common source 95 of supply to deliver bodies to the separate feeding devices, and a by-pass, associated with each of the separate feeding devices, through which excess bodies will be discharged in case of interruption in the normal 100 operation of a feeding device to thereby admit of the uninterrupted operation of the other feeding device.

3. A system of handling bodies including: two heading machines operating independently of each other, means for feeding bodies to said machines from a common source, and means whereby an interruption in the normal operation of one of said machines causes the discharge of bodies to thereby admit uninterrupted feeding of bodies to the other machine.

4. A system of handling bodies including: two heading machines operating independently of each other, means for feeding bodies to said machines from a common source, and by-passes associated with said feeding means through which excess bodies will be discharged in case of interruption in the normal 115 operation of one of said machines to thereby admit uninterrupted operation of the other machine.

5. A system of handling bodies including: two heading machines, separate body-feeding devices for each machine, a common 125 source of supply to deliver bodies to the separate feeding devices, a by-pass at the beginning and end of each separate feeding device through which excess bodies will be discharged in case of interruption in the nor- 130

- mal operation of a feeding device or machine to thereby admit of the uninterrupted operation of the other feeding device and machine.
5. 6. A system of handling bodies including: two heading machines arranged in series, a body-feeding device from one heading machine to the other and a by-pass through which excess bodies will be discharged in case of interruption of the normal operation of the feeding device.
7. A system of handling bodies including: two heading machines arranged in series, a body-feeding device from one heading machine to the other, and a by-pass through which excess bodies will be discharged from the feeding device in case of interruption of the normal operation of the second heading machine to thereby admit of the uninterrupted operation of the first heading machine.
8. A system of handling bodies including: two heading machines arranged in series, a body-feeding device from one heading machine to the other, and a by-pass at each end of the body-feeding device through which excess bodies will be discharged in case of interruption of the normal operation of the feeding device or of the second machine.
9. A system of handling bodies including: a plurality of heading machines arranged in parallel in two groups, the machines of each group being in series, separate feeding devices for each group, a common source of supply of bodies, a distributing device to separate the bodies from the common source and to feed them to the separate feeding devices, and by-passes through which excess bodies will be discharged in case of interruption of the normal operation of one group of machines or the feeding devices thereof to thereby admit of uninterrupted operation of the other group or in case of interruption of one of the machines or a feeding device of a group to thereby admit of uninterrupted operation of another machine of the same group.
10. A system of handling bodies including: a heading machine, an infeed conveyor, an outfeed conveyor, and a by-pass between the infeed conveyor and the machine and the outfeed conveyor and the machine through which excess bodies may be discharged.

Signed at Bridgeport in the county of Fairfield and State of Connecticut, this 15th day of January, 1925.

PAUL H. LANGE.
